L. SATTER

WRENCH

Filed Dec. 14, 1922

Inventor:
Lew Satter

UNITED STATES PATENT OFFICE.

LEW SATTER, OF WILEY, WASHINGTON.

WRENCH.

Application filed December 14, 1922. Serial No. 606,958.

To all whom it may concern:

Be it known that I, LEW SATTER, a citizen of the United States, residing at Wiley, in the county of Yakima and State of Washington, have invented a new and useful Improvement in Wrenches, of which the following is a specification.

The invention relates to improvements in pipe wrenches and nut wrenches, and the 10 objects of the improvement are:

First: To provide a pipe wrench with double acting jaws, easily and quickly adjustable to the service required and automatic in the release of same from the pipe 15 upon which it is used.

Second: To provide means for operating the jaws of the pipe wrench without the use of spiral screw, ratchets or other devices for moving same.

Third: To provide means for operating the jaws of pipe wrenches by adjusting same by a single movement of the parts of the wrench and without the use of spiral screw, ratchets, chains or other devices.

Fourth: To provide means for adjusting the jaws of pipe wrenches by automatically releasing the jaws upon an upward movement of the handle of the wrench.

In the drawings,
30 Figure 1 is a plan view of the improved pipe wrench.

Figure 2 is an edge view of the same, and

Figure 3 is a transverse section taken on the line 5—5 of Figure 1.

Referring to the drawings A and H are the two jaws or heads, the jaw H being carried by the bar X; while the jaw A is carried by the notched bar T.

A casing B envelops the two bars and is 40 pivoted to the bar X as indicated at I. Inwardly of the point I is the pivot point S for the pawl or dog L which is adapted to cooperate with the notches T and the pawl is provided with a pin or knob K projecting 45 through a slot in the casing B for manipulation of the pawl. The pawl is pressed by the spring J against the notches T.

In operation the wrench is placed upon

the pipe to be turned and the two jaws A and H are pushed together by hand. The 50 pipe may be turned. To loosen the wrench from the pipe the handle bar X may be lifted or the pin K depressed whereby to permit the separation of the jaws A and H.

I claim:

A wrench comprising a pair of substantially parallel bars adapted to move longitudinally with respect to one another, a handle on one of said bars, heads on both bars having mutual gripping teeth to receive 60 a pipe, one of said bars having a series of notches on its inner side, a casing enveloping both bars and pivoted to one of the bars, a pivoted pawl carried by said casing between the bars and adapted to cooperate with 65 the notches on said bar whereby to hold the jaws in substantially fixed position, said casing having a slot, a pin connected to the pawl and slidable through said slot, said casing having a closed wall against which the 70 outer face of the notched bar slides and abuts, said casing also having a second wall opposite the first mentioned wall against which the outer face of the companion bar is adapted to engage, said walls adapted to 75 prevent undue separation of the bars such as would cause the jaws to swing together and crush the pipe held therebetween, said notched bar having a limited lateral movement in and relative to the casing toward 80 the companion bar, said pivoted pawl having a plurality of teeth adapted to simultaneously engage the notches in the bar over a relatively wide area, a flat spring on such companion bar for urging the toothed portion of the pivoted pawl toward the notched bar and for yieldingly holding the notched bar against the first named closed wall of the casing, said toothed portion of the pawl being at an intermediate portion of said 85 casing and its first named closed wall, the pivot point of the pawl being inwardly of the pivot point of the casing toward said notched bar.

LEW SATTER.
